(57) **CLAIM**

The ornamental design for a sock and suspender assembly, as shown and described.

DESCRIPTION

FIG. 1 is a perspective view illustrating my design for a sock of the sock and suspender assembly, showing two holes through opposite sides of an upper portion.

FIG. 2 is a right-side view thereof.

FIG. 3 is a rear view thereof.

FIG. 4 is a left-side view thereof.

FIG. 5 is a front view thereof.

FIG. 6 is a top view thereof.

FIG. 7 is a bottom view thereof.

FIG. 8 is a perspective view illustrating my design for a sock and suspender assembly with a suspender clip attached to one of the two holes.

FIG. 9 is a right-side view thereof.

FIG. 10 is a rear view thereof.

FIG. 11 is a left-side view thereof.

FIG. 12 is a front view thereof.

FIG. 13 is a top view thereof; and,

FIG. 14 is a bottom view thereof.

The broken lines shown in the cuff of the sock depict claimed stitching.

FIGS. 8-14 include symbolic break lines along a portion of the suspender strap. The symbolic break lines and the areas between the symbolic break lines form no part of the claimed design.
